FILLING MACHINE

Max Goldberg, New York, N. Y.

Application May 10, 1937, Serial No. 141,841

5 Claims. (Cl. 226—125)

This invention relates to a machine for filling the casings of such articles as stuffed dolls, toys, etc., with fibrous materials such as cotton, cork, or straw.

6 An object of this invention is to provide a filling machine comprising a hopper superimposed over one end of a linked filling material carrier and having a nozzle in alignment with the carrier at its other end.

16 Another object of this invention is to provide a sprocket chain carrier, the links of which have integral angularly extending pusher arms and the said hopper having openings in two of its lower side walls permitting said arms to pass through

16 the lower portion of said hopper and carry portions of filling material therefrom to the nozzle end of the sprocket chain and push the material into the casing to be filled.

Another object of this invention is to design 20 the sprocket chain carrier so that when a pair of pusher arms deliver a batch of filling material into the nozzle they will immediately swing backwards from the nozzle and move with their coacting chain links below the nozzle.

25 Another object of this invention is to provide a supporting track below the sprocket chain so as to cause the pusher arms to move in a fixed horizontal plane during their movement into the nozzle.

30 With the above and other objects in view, the invention will be hereinafter more particularly described and shown in the accompanying drawings and pointed out in the claims which form part of this specification.

35 Reference will now be had to the drawings, wherein like numerals of reference designate corresponding parts throughout the several views, in which:

Figure 1 is a plan view of the filling machine.

40 Figure 2 is a vertical central sectional view, the section being taken as on line 2—2 in Figure 1.

Figure 3 is a fragmentary cross-sectional view, the section being taken as on line 3—3 in Figure 1.

45 Figure 4 is a fragmentary cross-sectional view, the section being taken as on line 4—4 in Figure 1, the sprocket chain and pusher arms being removed.

Figure 5 is a cross-sectional view, the section being taken as on line 5—5 in Figure 2.

50 In the illustrated embodiment of the invention, the numeral 10 indicates a casing filling machine comprising a frame 11 having an elongated bed or operating table 12 at its upper surface. The table 12 has two parallel longitudinal slots 13, 13.

55 Secured to the table 12 and in superimposed rela-

tion with the slots 13 is a hopper 14 into which the filling material is fed.

A sprocket chain 15 having pairs of pusher arms 16 fixed in right angular relation to alternate links is mounted on an idler sprocket wheel 17 and a driving sprocket wheel 18 below and in parallel relation with the operating table 12 and so that the pusher arms extend through the slots 13 above the operating table. A track 19 has been secured below the operating table 12 and provides a support for the links of the sprocket chain 15 and causes the pusher arms 16 to operate in a fixed path parallel with and above the operating table 12.

The idler sprocket wheel 17 is secured to a shaft 20 rotatably disposed within bearings 21. The bearings 21 are suitably supported in the frame 11 as by means of angle irons 22. The driving sprocket wheel 18 is secured to a drive shaft 23 rotatably disposed within bearings 24. 20 The sprocket chain 15 is also mounted on an idler sprocket wheel 25 which is secured to a shaft 26 disposed within bearings 27.

The sprocket wheel 25 has been positioned at a lower elevation than the sprocket wheels 17 and 25 18 so as to cause the sprocket chain 15 to move downwardly away from the bed 12 and carry the pairs of pusher arms 16 to a position below the nozzle. As shown in Figure 2, one end 29 of the nozzle 28 terminates substantially in line with the pitch circle 38 of the sprocket wheel 18 and when a pair of pusher arms 16 delivers a batch of filling material into the nozzle 28 the resistance of the compressed material in the nozzle stops the forward motion of the said pusher arms and causes said arms to swing about the rear pivot in the link with which it is integrally connected. Since the sprocket 25 is an idler the inclined portion of the chain is loose and under no tension. The said pusher arms are therefore free to swing 40 backwards and clear the nozzle while following a portion of the said pitch circle in its movement below the bed 12. The sprocket chain 15 is endless and with the pusher arms extending all around the chain forms a travelling conveyor 30. 45

The hopper 14 has two slots 31, 31, in the rear side wall 32 permitting pairs of pusher arms to pass therethrough. The hopper also has an opening 33 of nozzle size in the side wall 34 permitting the respective pairs of pusher arms and 50 batches of filling material to pass through in its passage to the nozzle 28.

As shown in Figures 2 and 4, the hopper 14 has perforations 35. These perforations may extend throughout the entire surface area of the hopper 55

or be limited to a portion thereof and serve to provide an outlet for air from the air blower of a processing machine (not shown) by means of which the material is fed to the hopper.

5. The opening 33 in the hopper 14 leads into an elongated covered passageway 36 into which the nozzle 28 extends. The pusher arms 16 project normally from the linked member 15 and extend substantially to the upper elevation of the nozzle.

10. In operation, the processed filling material is fed into the hopper 14 and the sprocket wheel 18 is rotated continuously in the direction shown by the arrow to cause the linked member 15 to move in a linear direction as guided by the 15 supporting track 19. Pairs of pusher arms 16, 16, grip batches of filling material from the hopper and deliver it into the nozzle 28 and into the casing 37 of a casing to be filled or stuffed.

15. In accordance with the provisions of the patent statutes I have described the operation of my invention, together with the device which I now consider to represent the best embodiment thereof; but I desire to have it understood that the device shown is only illustrative and 20 that the invention may be carried out by other means within the scope of the appended claims.

I claim:

1. In a filling machine of the character described comprising a covered passageway for 30 filling material, a linked driving member mounted for slidable motion in parallel relation with said passageway and said linked member having pusher arms integrally secured in right angular relation to the respective links and being 35 movable in said passageway, said linked member having an end portion in inclined relation with said passageway, said passageway terminating in a nozzle and said inclined portion of said linked member being positioned below said nozzle, said inclined portion of said driving member being rotatably mounted on a toothed idler wheel at its lower elevation.

2. In a filling machine of the character described comprising an elongated passageway for 40 filling material, a linked driving member mounted for motion in an elongated linear direction in parallel relation with said passageway, said linked member having integral pusher arms integrally secured in right angular relation to the 45 respective links and being movable in said passageway, said linked member having an end portion in inclined relation with said passageway and being mounted on and meshing with a toothed idler wheel positioned at an elevation below said elongated linear portion of said driving member.

55. 3. In a filling machine of the character de-

scribed comprising an elongated passageway for filling material, a linked driving member mounted for motion on an elongated linear supporting track positioned in parallel relation with said passageway, said linked member having pairs of integral pusher arms secured to alternate links and being movable in said passageway, said linked member having an end portion in inclined relation with said passageway and being mounted on and meshing with a toothed idler wheel positioned at an elevation below said elongated linear portion of said driving member.

4. A filling machine of the character described, comprising a bed having an elongated passageway for filling material thereon, a linked driving member mounted for motion on two sprocket wheels and an elongated linear supporting track, said track being positioned between said sprocket wheels and in parallel relation with said passageway, said linked member having pairs of integral pusher arms secured to alternate links and being movable in said passageway, a hopper secured to said bed and being superimposed over one end of said linked member, a nozzle secured to said bed and in alignment with said linked member at its other end, said linked member having an end portion in inclined relation with said passageway and being mounted on and meshing with a toothed idler wheel positioned at an elevation below said elongated linear portion of said driving member, whereby said pusher arms after discharging filling material into said nozzle are carried below the nozzle.

5. A filling machine for casings, comprising a bed having thereon an elongated passageway for filling material, a linked driving member mounted for motion on two sprocket wheels and on an elongated supporting track, said track being positioned between said sprocket wheels 40 and in parallel relation with said passageway, said linked member having pairs of pusher arms secured to alternate links and extending into said passageway, a hopper superimposed over one end of said linked member, a nozzle forming a continuation of said passageway and being in alignment with said arms at the other end of said linked member, said linked member having an end portion in inclined relation with said passageway and being mounted on and meshing with a toothed wheel positioned at an elevation below said elongated portion of said driving member, whereby said arms after discharging filling material into said nozzle are carried below and clear of said nozzle.

MAX GOLDBERG.
